RIVET SETTING MACHINE

Louis C. Huck, Grosse Pointe Village, and George T. Chapman, Will E. Morris, and Ralph A. Miller, Detroit, Mich., assignors, by direct and mesne assignments, to Huxon Holding Corporation, Detroit, Mich., a corporation of Michigan

Application October 6, 1932, Serial No. 636,480
Renewed May 5, 1934

79 Claims. (Cl. 218—19)

The invention relates to fastening mechanisms and it has particular relation to an apparatus for applying rivets to structural elements for securing them together.

- 5 In the copending application for patent of Louis C. Huck, relating to rivets, Serial No. 545,004, filed June 17, 1931, a rivet is illustrated which comprises a female member having a tubular body portion and a rivet head formed at one end thereof, and a male or shank member extending longitudinally through the female member and which has a head at one end engaging that part of the female member opposite the head on the latter. This shank or male member 10 extends through and beyond the head on the tubular member to provide a gripping portion. The rivet as thus assembled may be inserted through structural openings until the rivet head on the female member engages one side of the structure. 15 In setting the rivet, the projecting portion of the male member is gripped and pulled while the reactionary force is applied to the head on the female member adjacent thereto and as the male member is pulled, the head thereon at the opposite end of the female member causes an outward bulbing of the body portion of the female member between the structure and the head on the male member, to form a bulbed head at the opposite side of the structure. 20 In the co-pending application of Louis C. Huck relating to rivets, Serial No. 599,868, filed March 16, 1932, a rivet of this general type is illustrated but certain desirable improvements are incorporated therein. In the first place, the dimensions 25 of the male and female members and particularly the dimensions of the body portion of the female member to be bulbed into a head, and the materials employed in the male and female members are such that during the initial pulling of the 30 male member, the body portion of the female member is so axially compressed and the metal is so upset that any spaces or interstices existing between the sides of the opening in the structure being riveted and the female member, as well as 35 the spaces between the male and female members, are closed for the purpose of rendering the connection very tight. Subsequently to this initial 40 phase of the rivet setting operation, the body portion of the female member between the head and the male member and the structure being riveted is outwardly bulbed into a head and then upon 45 further pulling of the male member, it breaks at a point determined by location of a groove or break neck in the male member which is located 50 following the bulbing of the head, substantially 55

at the outer face of the head of the female member, although of course this groove may be located at any other point desired. The groove of undercut character naturally provides a portion in the male member of weaker construction and in this manner the breaking point is determined. As illustrated and described in this co-pending application, the projecting end of the male member preferably is provided with grooves or threads to facilitate the gripping thereof. 10

Generally these features or improvements are also incorporated in the co-pending application of Louis C. Huck, Serial No. 604,759, filed April 12, 1932, although in this construction it has not been found necessary to initially bulb a small 15 and thinner portion of the female member adjacent the head on the male member, to reinforce the end of the female member against bursting during the subsequent formation of the main bulbed head. 20

While the rivets described and illustrated in the aforesaid copending applications for patent have been very satisfactory, considerable thought has been given to the effect of the recoil on the male member in the rivet when its projecting end has 25 been broken. Considerable force is required to set the rivet and a still larger force is required to break the male member at the undercut or groove after the bulbed head is formed and when this break occurs, there is naturally considerable 30 recoil and it has been thought possible that this recoil may cause slight loosening of the rivet connection. In view of the fact that the male member and female member adjacent the head 35 on the former are locked together when the rivet is set, this recoil on the male member following breaking thereof at the groove, and possibly inherent resilient characteristics of the bulbed head tend to move the pin slightly in a direction opposite that in which it is moved during the rivet 40 setting operation. It seems that by providing a rivet such as will hereinafter be described and illustrated, and setting it in a certain manner and with the machine illustrated, the effect of 45 this recoil may be largely neutralized if not obviated. At any rate it seems that a rivet of the character described may be made tighter and this invention particularly is related to a machine for setting a rivet so as to obtain a tighter and 50 stronger rivet connection. Primarily it has been 55 found that if the female member, and particularly that portion of the female member adjacent the initially formed head, is locked to the male member adjacent the groove provided therein for breaking purposes, prior to the breaking of the

male member and subsequent to formation of the bulbed head, any recoil effect, including possible resilient return of the bulbed head, will be substantially prevented by this locking engagement 5 or in other words this effect will be substantially absorbed by the head portion on the female member adjacent the break. The co-pending application for patent of Louis C. Huck, Serial 627,343, filed August 3, 1932, relates to rivets of this character.

One object of this invention is to provide an apparatus or machine for setting rivets of the above-mentioned character, which locks the male and female members positively at that end of 15 the latter opposite the bulbed head.

Another object of the invention is to provide an apparatus wherein a force directed in a direction opposite to the force pulling the male member, is employed to lock the male and female 20 members as set forth above.

Another object of the invention is to provide an apparatus of the above designated character in which the male and female members are locked in the manner set forth, after the female 25 member has been bulbed to form a head, and prior to breaking the male member as stated.

Another object of the invention is to provide means for locking the male and female members together, comprising an anvil adapted to swage 30 the head of the female member on to the male member.

Another object of the invention is to provide power means for ejecting the head of the female member from the swaging anvil upon completion 35 of the swaging operation and after the male member is broken.

Another object of the invention is to provide an apparatus for locking the male and female members together in the manner set forth, 40 wherein the initially formed head on the female member is disposed in a countersunk opening in the structure being riveted.

Another object of the invention is to provide an apparatus for optionally setting a rivet having either type of head, and locking the parts 45 as set forth.

Other objects of the invention will be apparent from the following description and the claims hereinafter set forth.

50 For a better understanding of the invention reference may be had to the accompanying drawings forming a part of the specification, wherein:

Figure 1 is a longitudinal cross-sectional view 55 of a rivet setting machine constructed according to one form of the invention, and also illustrates a pressure boosting device for supplying fluid under pressure to the machine.

Fig. 2 is an end view of the machine shown 60 by Fig. 1, as seen from the left end thereof, and also illustrates a valve construction in cross section.

Fig. 3 is a cross-sectional view on a larger scale 65 taken substantially along the line 3-3 of Fig. 1. Fig. 4 is a cross-sectional view taken substantially along the line 4-4 of Fig. 1.

Fig. 7 is a cross-sectional view on a larger scale, taken substantially along line 7-7 of Fig. 1.

Fig. 8 is a fragmentary elevational view of the 75 machine shown by Fig. 1, illustrating the gen-

eral interlocking arrangement shown by Fig. 7.

Fig. 9 is a fragmentary cross-sectional view of the machine illustrating its selectivity of operation for setting of rivet of a different type.

Fig. 10 is a cross-sectional view taken substantially along the line 10-10 of Fig. 9.

Fig. 11 is a cross-sectional view taken substantially along the line 11-11 of Fig. 9.

Fig. 12 is a cross-sectional view illustrating a rivet inserted in a structure to be riveted, where- 10 in the rivet is particularly adapted to be set by the machine as illustrated in Fig. 1.

Fig. 13 is a view similar to that shown by Fig. 12 illustrating the rivet after it has been set.

Fig. 14 is a cross-sectional view of another type 15 of rivet inserted in a structure which is particularly adapted to be set by the machine when employed in the manner shown by Fig. 9.

Fig. 15 is a cross-sectional view illustrating the rivet shown by Fig. 14, after it has been set. 20

Attention is first directed to Fig. 12 illustrating a rivet particularly adapted to be set by using a machine hereafter to be described. In this figure structural elements 10 and 11 to be riveted are illustrated and it will be understood that initially an opening will be provided in the structure for receiving the rivet. The rivet shown 25 comprises a tubular member 12 having a head 13 at one end preferably tapered on its outer surface at an angle to the rivet axis, for engaging 30 the outer side of structural element 10, and which at its other end has a radially and inwardly projecting portion 14 disposed in a groove 15 formed in a pin 16 extending through the tubular member. Adjacent the groove 15, the pin is provided with a head 17 engaging the end face of the tubular member, whereas the opposite end of 35 the pin projects beyond the outer face of the head 13 and is provided with threads or grooves 18 for cooperating with similar threads or grooves 40 provided in the gripping surfaces of jaws in the machine. Intermediate its ends, the pin is provided with several threads or grooves 19 and a break neck or slightly deeper groove 20. In setting a rivet of this character, the threaded or 45 grooved portion 18 of the pin is gripped and pulled while the reactionary force is applied against the head 13 of the tubular member and during this operation, movement of the head 17 causes an outward bulbing of the body portion of the 50 tubular member between the structural element 11 and such head on the pin, to provide a bulbed head as indicated at 21 in Fig. 13. It may be stated at this time that the radial projection 14 on the tubular member, disposed in the groove 15 on the pin, reinforces this end of the tubular member and insures proper bulbing to form the head 21 without danger of the head 17 on the pin passing through the tubular member and possibly bursting it. When the head 21 is formed 55 as shown in Fig. 13, the break neck 20 preferably is located adjacent the outer face of the head 13 on the tubular member, and following setting of the head, a continued and more forceful pull on the pin will tension it sufficiently to break it at such break neck as illustrated in Fig. 13. Prior 60 to breaking the pin, it has been found very desirable to positively lock the tubular member and pin adjacent the head 13 on the former, so as to neutralize or at least largely avoid any undesirable result that might occur because of the recoil on the pin remaining in the tubular member, or resilient return of head 21 following breaking of the pin under tension. Considerable force 65 is required to break the pin and at the break, it 70

75

will readily be appreciated that the recoil might be effective to move the pin slightly in the direction opposite that in which it was moved to set the rivet and thus loosen the rivet connection.

5 Owing to the lock between the tubular member and the pin adjacent the head 17, any slight movement of the pin in such reverse direction necessarily affects the bulbed head 21 and in fact the latter may have inherent resiliency to 10 even assist the action of the recoil force. It will thus be seen that it is desirable to prevent largely, if not entirely, the action of the recoil on the pin after breaking thereof, and to prevent any loosening of the connection as a result of this 15 recoil or the recoil in combination with the inherent resiliency of the head 21 following its formation. As a means for locking the pin and tubular member adjacent the head 13, the grooves 19 have been provided, and following 20 forming of the head 21 and tightening of the plates, and prior to breaking of the pin, the metal in the tubular member adjacent and in the head 13, is directed radially and inwardly into the grooves 19 as indicated in Fig. 13. This 25 is effected between the head forming operation and the pin breaking operation, by contracting at least a portion of the head 13, into the grooves 19, the contracted portion being indicated in Fig. 13 at 22. Then upon breaking of the pin, 30 it is apparent that the interlocking of the tubular member adjacent to and in the head 13, with the grooves 19 in the pin, will largely, if not entirely, prevent any backward movement of the pin, upon breaking thereof. The machine illustrated 35 in Fig. 1, is particularly adapted to set this rivet, direct the metal in the tubular member into the grooves 19 as described, and then to break the pin.

It has been mentioned above that prior to 40 breaking of the pin, the metal in the tubular member adjacent and in the head 13 is directed radially and inwardly into the groove 19. In certain instances herein, and in the claims, the terms "upsetting" or "swaging" are used to 45 describe the operation by which a flow of metal is effected to obtain a locking engagement. It is to be understood that these terms are intended to define any operation by which the metal is moved or flows and that they should not be subject to any more limited construction such as 50 they may have in the metal working art.

Referring to Fig. 1, a machine illustrated for 55 setting the rivet comprises a casting 23 having a handle portion 24, and such casting and handle portion thereof have passages 26 and 25 respectively. Adjacent the handle portion, a trigger 27 is provided which is adapted to operate a normally closed valve 28 that closes the passage 25 to the atmosphere, a port 29 being provided to 60 communicate the passageway 25 with the atmosphere when the valve is open. When the valve is closed, the passage 25 is in communication with a second passage 30 having a ball check valve 31, and which in turn communicates with a cylinder 32. Passage 25 is connected to a flexible fluid pressure line such as a compressed air line indicated at 33 and, accordingly, it will be understood that when the valve is closed fluid 65 or air under pressure may, if necessary, flow past valve 31 and to the interior of cylinder 32, whereas when the valve is open, the passage 25, passage 30 to the valve 31, and hence the pressure line 33 communicate directly with the atmosphere.

70 Passage 26 is provided to conduct fluid under

pressure such as oil, to other parts of the machine hereinafter described, and for this purpose a flexible oil pressure line 34 communicates with such passage. The line 34 is connected to a barrel 35 having a plunger therein, and this 5 plunger in turn is connected to a piston provided in a cylinder 36. Movement of the piston in cylinder 36 is effected by air pressure from an air pressure line 37 connected to a valve mechanism 38 and the latter through conduit 33 is 10 controlled by trigger 27.

The mechanism so far described, except for the check valve 31, is substantially identical to the rivet setting machine disclosed in the co-pending application of Louis C. Huck and George T. Chapman, Serial No. 615,544, filed June 6, 1932, and for this reason it seems only necessary to briefly describe the operation of this part of the mechanism. When the trigger 27 is pulled, passage 25 and passage 30 to check valve 31 communicate 20 with the atmosphere and the reduction in pressure in the air line 33 so operates the valve mechanism 38 that the piston in cylinder 36 and plunger in barrel 35 move to the left, causing a pressure on and flow of the oil through the conduit 25 34 and through the passage 26. The relative diameters of the plunger in barrel 35 and the piston in cylinder 36 is such that with an ordinary air pressure, a pressure on the oil is obtained which is many times that of the air pressure. 30

The cylinder 32 is of a dual type or, in other words, two cylinder bores 39 and 40 are provided and an air passage 40' connects them so that air from passage 30 may flow to the right end of cylinder 39 and the left end of cylinder 40. A piston 41 is reciprocatory in cylinder 39 and a piston 42 is reciprocatory in cylinder 40, piston 41 being rigidly connected to a piston rod 43 which is slidably in opposite end walls of the cylinder 40 indicated at 44 and 45, and in a central wall 46 separating the cylinder bores. Piston 42 is slidably mounted on the piston rod 43. At opposite ends of cylinder 39, cup washers 47 are provided and it will be noted that these washers are so formed that pressure within the cylinder tends to contract their rim portions around the piston rod and hence to more positively seal the cylinder against the escape of fluid therein. Each piston is provided with flexible cup washers 48 and 49 disposed in opposed relation and at opposite sides of the piston with their rim portions pressed outwardly against the cylinder wall. It is evident that the pressure in the cylinder tends to expand the rim portions of the washers against the cylinder wall and in this manner substantially prevents the escape of fluid past the piston. The piston 41 has one or more radially disposed vents 50 communicating with the exterior of the periphery of the piston between the cup washers, which at their inner ends communicate with a centrally located opening 51 extending longitudinally of the piston rod and communicating with the atmosphere at the right end of the cylinder. Piston 42 similarly has one or more vents 50 communicating with a groove in the inner periphery of the piston, indicated at 52 and this groove in turn communicates with an axial slot 54 extending longitudinally of a sleeve portion 55 integral with piston 42 and which is slidably mounted on piston rod 43 and slidably projects through cylinder wall 45. One of the cup washers 47 is also mounted in the wall 45 around the sleeve 55. For allowing exhaust of fluid such as air that may escape through vents 50 and slot 54, an opening 55

55' may be provided in the rod 43 beyond the end cylinder wall 45, and this vent also prevents trapping of fluid in the machine beyond this wall. The rod 43 is threaded into a tubular member 56 and the latter in turn is threaded into a sleeve 57, the outer end of which, as best shown by Fig. 3, has three sockets 58, 59, and 60 which are of cylindrical character. Each of these sockets at its end shown in Fig. 3, is semi-cylindrical or 10 slightly less than semi-cylindrical in form, but inwardly from the end of the sleeve, each socket in longitudinal cross section, diverges outwardly from the longitudinal axis of the sleeve, and the form of the socket over a substantial linear portion thereof is greater than semi-cylindrical in form. The inner ends of the sockets which are greater than semi-cylindrical in form, are indicated in broken lines at 61, 62, and 63. Each socket receives a jaw 64 having an outer cylindrical surface complementary to the surface of the socket and the longitudinal axis of which is directed parallel to the axis of the socket. The inner gripping surface of each jaw indicated at 65, while substantially cylindrical has grooves or 20 teeth 66 and is directed in coinciding or parallel relation to the axis of the sleeve. It will, therefore, be evident that in a movement of the jaws toward the outer ends of the sockets, they move radially toward each other, although the gripping surfaces are maintained parallel to the axis of the sleeve. This construction insures uniform and full contact of the gripping surfaces with a cylindrical rivet pin extending between the jaws, throughout the length of the gripping surfaces, 30 regardless of movement of the jaws in their sockets.

Each jaw, as best shown by Fig. 1, terminates at its inner end in a groove portion 67 which is interlocked with a tubular pin 68 slidably mounted in the tubular member 56. The pin 68 is longitudinally apertured as indicated at 69, and this aperture coincides with the aperture 61 in the piston rod 43, from which it follows that from the jaws a continuous passage exists through the machine which is open to the exterior of the end wall 44 of the cylinder. For the purpose of normally urging the jaws toward the outer end of the sleeve, and into gripping position, a helical spring 70 encircles a reduced portion 71 of the member 56 and abuts a shoulder 73 on the pin 68. A ring of rubber or the like 72 also is mounted on pin 68 adjacent shoulder 73 and is adapted to engage the end of member 56 when the jaws move inwardly as will be later described. For the purpose of facilitating removal of the jaws from the parts associated therewith, the sleeve 57 at circumferentially spaced points is provided with elongated openings 75 that are so located, that upon moving the jaws inwardly, they may be expanded sufficiently to disengage them from the pin 68 when sleeve 56 is removed, although it will be understood that a movement of the jaws sufficiently to effect such disengagement normally can not occur when sleeve 56 is in place.

Referring again to Fig. 1, at the left side of the end wall 45 on the cylinder, a tubular casting 85 is fastened and such casting on its inner periphery has a cylindrical recess of substantial length indicated at 86. The sleeve portion 55 connected to piston 42 is connected by threading to a member 87 movable in the recess 86 in casting 85. This member 87 as shown by Fig. 6 has three radial projections 88 spaced equally in a circumferential direction and each projection terminates in an axially disposed leg 89. The end

wall 45 of the cylinder also is provided as shown by Fig. 6 with three axially directed legs 90, which are spaced circumferentially and between which the radially directed projections 88 and legs 89 on the member 87 are adapted to move longitudinally of the piston rod. It will be noted, as shown by Fig. 1, that the legs 90 on the end wall 45 of the cylinder project substantially the same distance from the end wall as the legs 89 on member 87 when the latter is abutting such end 10 wall. It will be evident that if piston 42 is moved to the left, the reciprocating member 87 connected thereto may be moved longitudinally of the piston rod, with the three projections 88 and legs 89 thereon axially moving between the respective legs 90 on the end wall of the cylinder. 15

Each of the legs 89 and 90, as best shown by Figs. 7 and 8, at one circumferentially disposed edge, has a hook 91 and at its other circumferentially disposed edge, a notch 92. It will be noted 20 that the legs 90 on wall 45 substantially fit between the radial projections 88 on member 87 so that the legs 90 substantially guide member 87 in any reciprocating movement effected by piston 42. 25

Two sleeves or barrels 94 and 95, shown best by Figs. 1, 4, 5, and 8 particularly are slidably and rotatably mounted in the tubular member 85, and slidably mounted one within the other. The inner sleeve 95 at its right end, as shown by Figs. 1 and 4, has three axial slots 96, equally spaced circumferentially, the axial portions or legs between slots being indicated at 97. The outer sleeve 94 has at its right end, three equally spaced, radially and inwardly directed projections 98, 30 slidably disposed in the slots 96. Each of the legs 97 and the projections 98, as best shown by Fig. 7, has an axially projecting hook 99 adapted to cooperate with one of the hooks 91 on the legs 89 and 90 formed on the member 87 and cylinder 40 wall 45, respectively. From Fig. 7, it is evident that the notches 92 on the latter legs permit entry of the hooks 99 between such legs, and that after such entry, the sleeves 94 and 95 may be turned slightly until the hooks interlock as shown 45 in the figure. It will be noted that the sleeves turn as a unit because of the disposition of projections 98 on sleeve 94 in the slots 96 in sleeve 95.

With the parts arranged as shown by Figs. 1 and 7, the legs 97 on sleeve 95 abut the ends of legs 90 on the cylinder wall 45 while the ends of projections 98 on sleeve 94 abut the ends of legs 89 on the member 87 connected to piston 42. Now should the piston move to the left, member 87 will move sleeve 94 to the left, while leaving sleeve 95 stationary and against legs 90. This arrangement may be reversed by turning both sleeves slightly to free hooks 99 from hooks 91, then pulling the sleeves away from legs 89 and 90 until the hooks 99 are slightly beyond the ends of the legs, then turning the sleeves 60° to position projections 98 in axial alignment with legs 90, then moving the sleeves axially and the hooks 99 into the new entry openings therefor between legs 89 and 90, and then reversely turning the sleeves to engage the hooks. Now the hooks 99 on sleeve 94 engage hooks 91 on cylinder wall 45, and hooks 98 on sleeve 95 engage hooks 91 on member 87. Then any movement of the piston 42 will move sleeve 95 to the left, leaving sleeve 94 stationary. 65 70

For locking the sleeves 94 and 95 to the tubular member 85, while still permitting axial movement of the sleeves therein, a set screw 100 may be threaded through member 85 and selectively into any one of 60° spaced, axially elongated slots 101 75

in the sleeve 94. When it is desired to reverse the sleeve positions by turning them through 60°, it is only necessary to remove this screw, manipulate and turn the sleeves through 60° and then rein-
5 sert the screw into another of the openings.

The hooks are chiefly provided to insure return of either sleeve with a return movement of the piston 42. During setting of a rivet, abutting of the legs 89 and 90 with the ends of the sleeves re-
10 spectively is mainly important, but after setting of the rivet, that sleeve moved by the piston 42 should be returned with the piston.

The outer end of the inner sleeve 95 has an anvil 107 threaded thereinto and such anvil has a central opening 108 through which the pin 16 of the rivet may be inserted. This anvil terminates in a tubular portion 109 adapted to directly engage the head 13 on the tubular rivet member and to engage such head immediately adjacent to and around the pin. The outer tubular member 94 terminates adjacent the inner sleeve and a secondary anvil 110 is threaded thereinto and this anvil has a central opening 111 through which the tubular portion 109 on the anvil 107 projects for engagement with the head on the female rivet member. The opening 111 terminates in a bevel 112 which is adapted to slide over and contract head 13 on the tubular rivet member.

30 Now referring to the passage 26, it will be noted that it communicates directly with the cylinder 39 at the left side of piston 41 so as to allow oil under pressure to flow directly from barrel 35 to this end of the cylinder. The passage also 35 communicates with a bypass 115 leading to a valve chamber 116. Aligned with this chamber, a valve sleeve opening 117 is provided in the casting for receiving a sleeve 118, held in the opening by a screw cap 119 threaded into the casting. The sleeve 118 at its upper end abuts a sealing gasket 120 and adjacent thereto and the chamber 116, has a pilot 121 and a seat 121'. A valve 122 slidably mounted in the sleeve, terminates at its upper end in a reduced portion 45 123 providing an annular space 124 between the valve and sleeve immediately adjacent the seat 121'. This reduced end has a tapered portion 125 for engaging the seat 121'.

40 Adjacent its lower end, the valve has a head 126 slidable in a larger portion of the sleeve and on the shoulder thus provided, a resilient cup ring or washer 127 is provided to seal the head in the enlarged portion of the sleeve. Normally, when the 45 valve is seated, the head 126 and washer 127 are slightly spaced from the shoulder on the sleeve, as indicated at 128, at the junction of the enlarged portion of the latter, and this space is in communication with the annular space 124 around the valve adjacent the seat, by means of a passage 129 diametrically extending through the valve. Below the annular space 124, the sleeve has apertures as indicated at 130, and these apertures communicate with an annular groove 130' in the casting, in turn communicating with a passage 131 leading to cylinder 40 at the right side of piston 42. A sealing ring 132 around the sleeve below the aperture 130 and on the shoulder of such sleeve seals the outside of the sleeve at this 50 point.

For normally holding the valve closed, a plunger 133 abuts the valve and is slidable through the end wall of cap 119 but is limited in its downward movement by a shoulder 133'. A spring 134 abutting a collar 135 on the plunger at its upper

end and the end wall of the cap, holds the plunger and valve in their upper positions.

For permitting a return flow of oil from cylinder 40 through cylinder 39 and passage 26, even though valve 122 is closed, a spring pressed ball 5 valve 136 is provided in an aperture 137 in the wall 46 between the cylinder bores. This valve however prevents oil from flowing in a reverse direction from cylinder 39 to cylinder 40.

The valve 122 is of such character that oil 10 under pressure will flow into cylinder 39 and move piston 41 to the right, and build up to a considerable pressure before the valve will open. When the oil pressure acting on the upper end face of the valve within pilot 121, is sufficient to 15 overcome pressure exerted by the pre-loaded spring 134, it will open, allowing oil to flow into space 124, passage 129, and into space 128. Due to the added area of the valve head 126 below space 128 and the shoulder area on the valve 20 defining space 124, a pressure materially lower than that originally required to lift the valve off seat 121' will further overcome the pressure of spring 134 and cause the valve to open until shoulder 133' engages the end wall of cap 119 25 around the opening therein for the plunger, in which position, the space 124 registers with groove 130' and openings 130. The action of the valve is such that oil pressure will act against the aforesaid areas additional to the end face 30 of the valve, before the valve admits oil to build up a pressure in the space in cylinder 40 at the right of piston 42. Normally a certain amount of motion of piston 42 may occur before anvil 110 engages the head 13, and the flow of oil to 35 cause this motion, against very little resistance, tends to create a drop in oil pressure in cylinder 39. Preferably the dimensions of openings and parts, and the operation of the oil pressure supply means is such as to obtain this drop in oil 40 pressure in cylinder 39.

In setting the rivet as shown by Fig. 1, the trigger 21 is pulled, thus causing oil to flow through the passage 26 into the cylinder 39 at the left side of piston 41. This causes a movement of the piston to the right, carrying with it the sleeve member 47 and as this sleeve moves it causes contraction of the jaws 64 around the pin of the rivet and after positive gripping of the pin by the jaws, a movement of the pin to the 50 right. As this occurs, the reactionary force to the pull is directed against the head 13 of the tubular rivet member through the anvil 107 and its tubular projection 109, it being apparent that the inner sleeve 95 carrying this anvil is then 55 engaged by the projections 90 on the end wall 45 of the cylinder so that the reactionary force is taken directly by this cylinder wall.

As the pin of the rivet continues to move, the head 21 is formed as shown in Fig. 13, at the 60 inner side of the structure being riveted. After the head is formed, continued and somewhat increased tension on the pin, causes further tightening of the plates being riveted, to provide a tight rivet connection. When the pressure on 65 the oil at the left of piston 41 reaches a predetermined amount, sufficient to accomplish the aforesaid results, valve 122 will open as previously described and oil will immediately flow into cylinder 40 and begin to move piston 42 carrying the 70 secondary anvil 110. Some movement of the piston 42 and anvil 110 will occur before the anvil engages head 13 on the rivet and encounters any great resistance to its movement, and accordingly there will be a drop in oil pressure in pas- 75

sage 26 and cylinder 38. Valve 122 will normally remain open however because of the increased pressure area provided as previously described. Reduction of the pressure on the oil in cylinder 39 will allow some relaxing of the tension on the rivet pin and accordingly a little reversed movement of the pin through the tubular rivet member, due to the resilient return of the bulbed head 21. The relaxing of tension on the pin is desirable during seating of the anvil 110 on head 13 of the rivet and particularly so in the event the head is slightly eccentric or the anvil does not at first concentrically fit the head. As the anvil 110 meets further resistance to its movement by engaging head 13, the pressure on the oil against both pistons increases, and as piston 41 increases the tension on the pin and pulls it to the right, again overcoming any resiliency of the head 21, the anvil 110 contracts the head 13 and causes metal to flow into the grooves 19 in the pin. Simultaneously, a certain amount of extrusion of metal in head 13 occurs and results in some elongation thereof in the direction the pin is being pulled. This simultaneous extrusion of head 13 and tensioning and movement of the pin, insures filling of the grooves 19. It seems that with certain proportioning of the diameter, length and taper of head 13, and the dimensions of opening 111 and bevel 112 in anvil 110, the extrusion process and filling of the grooves may add materially to the tension to which that part of the pin to the left of the part engaged by the metal flowed in from head 13, is subjected by piston 41.

35 This lengthening of head 13, acting through anvil 107 and the cylinder may cause such movement thereof relative to piston 41 so as to cause some of the oil to flow back into the system and into passage 26. Finally the tension on the pin 40 is sufficient to break it at the break neck 20.

After the pin is broken, the trigger may be released but attention is directed to the fact that as the pin breaks the recoil on the jaws ordinarily is sufficient to cause them to loosen relative to the jaw receiving sleeve 51 and this recoil also may be sufficient to move the broken pin member backwardly through the jaws. In any event, upon insertion of an additional rivet pin between the jaws, the broken pin member of the 45 rivet set previously, if it has not moved rearwardly through the jaws, will be moved rearwardly therethrough upon inserting the next rivet. Thus the broken pin parts may be progressively moved through the jaws and finally 50 be ejected from the rear end wall 44 of the cylinder. As the pin breaks, rearward movement of the jaws and pin 68 relative to the sockets is cushioned by spring 70 and the rubber ring 72, the latter preventing metal engagement of the 55 pin with member 56.

During the riveting operation, the air trapped in the cylinders by ball valve 31, naturally is compressed to a much greater pressure and while this pressure acts as a cushion and in opposition to the movement of the pistons, it is small in view of the very great oil pressure obtained. However, as soon as the trigger is released after the riveting operation, the oil pressure is 60 moved because of return movement of the oil plunger in the booster device, and the high pressure of the air in the cylinders becomes effective to insure a quicker return of the pistons, oil plunger and piston in cylinder 36 to their 65 original positions. Thus return of the parts 70

accordingly is accelerated with an air pressure higher than line pressure in conduit 33.

It should be noted that the return movement of piston 42 to the right under air pressure, as above described, necessarily is accompanied by 5 movement of anvil 110 to the right with respect to anvil 107, inasmuch as anvil 110 is locked to the piston 42 by sleeve 94, sleeve projections 98, hooks 99 and 91, members 89 and 87 and piston sleeve 55, whereas anvil 107 is prevented 10 from moving to the right by reason of the abutment of legs 97 on sleeve 95 with legs 90 formed on the cylinder wall 45.

As a result of this relative movement between anvils 110 and 107 under the influence of relatively high air pressure at the left side of piston 42, the rivet heads 13 will be forcibly ejected from the swaging anvil 110. This is of considerable advantage as the very high swaging pressure tends to jam anvil 110 over the rivet head, 20 rendering it difficult to remove the anvil after the rivet setting operation is completed. It may be noted that ejection of the rivet head will not tend to loosen the rivet since anvil 107, which acts as an ejecting member during this period, 25 engages the rivet head itself.

To prevent the operator from holding the trigger open after the riveting operation is completed, and thus to prevent the piston 41 from being forcefully thrown against the cylinder wall 30 44, a lever 144 is pivoted on the casting in the path of movement of the piston rod 43, and upon a certain movement of the rod, it engages this lever. The lever is connected to the trigger to throw it to its closed position, forcibly 35 overcoming any manual pressure on the trigger.

Under certain circumstances it may be desired to use a rivet in which the tubular member has a countersunk head 150, as shown by Fig. 14, which is disposed in a correspondingly countersunk opening in the structure. In this case, it is impossible to contract the outer periphery of the head in the manner described with respect to the rivet shown by Fig. 12. In order to obtain substantially the same result however, 45 the head may be provided with a cylindrical groove 151 around the pin and at the outer face of the head, and this groove may merge into a beveled surface 152. In assembling the rivet, a metal ring composed of metal similar to that 50 of the tubular member, may be inserted as indicated at 153 into the cylindrical groove 152. In setting a rivet of this character, as the pin is pulled, the reactionary force is applied directly to the head at a point radially and outwardly with respect to the ring 153 and after the head is formed as shown by Fig. 15, a secondary anvil is brought into operation which 55 engages the ring 153. As this secondary anvil becomes effective, it forces the ring 153 against the tapered surface 152 and thus forces it into locking engagement with threads 154 on the pin. This occurs prior to breaking of the pin so that upon the latter occurring the recoil will be effectively neutralized by the interlocking engagement of the ring with the pin and its engagement 60 with the tapered surface 152 on the tubular member.

In setting a rivet of this character, the machine is used, shown by Fig. 1, except for a 70 changing of arrangement and anvils. The anvils 107 and 110, shown in Fig. 1, are removed, and in place thereof anvils 160 and 161 are provided, as shown by Fig. 9. The anvil 161 has a plane portion 162 adapted to engage the coun- 75

tersunk head 150 on the tubular member around the cylindrical groove, while the anvil 160 has a tubular projection 163 slidably passing through a central opening in the anvil 161 and adapted 5 to engage the ring 153. In the machine as described with respect to Fig. 1, it will be recalled that the central anvil 167 initially applies the reactionary force to the head on the female member and that after the bulbed head 21 is 10 formed, the outside anvil comes into action to contract the head. In the type of rivet last described, and shown by Fig. 14, it is necessary that the outside anvil initially apply the reactionary force, and after the bulbed head is 15 formed, that the inside anvil apply the secondary and force required to upset the ring 153. After the anvils are interchanged as mentioned, it is only necessary to remove the threaded screw 100 which is used to lock the sleeves 94 and 95 20 against circumferential movement with respect to the member 85 and after this screw is removed, the sleeves may be rotated. If these sleeves are rotated 60 degrees, it is apparent that the projections 97 on the inner sleeve 95 will 25 now be brought into axial alignment with the projections 89 on the member 87 and that the projections 98 that were aligned with the projections 89, will be brought into axial alignment with the projections 90. When so positioned and 30 the hooks 91 and 99 are interlocked, the set screw may be inserted and projected into the proper slot 101 formed in the sleeve 94. The result of this is that the piston 42 is now operatively connected to the inner sleeve whereas the 35 outer sleeve is directly engaged by the end wall of the cylinder. Upon setting a rivet of this character, when the trigger is pulled, oil under pressure causes a movement of the piston 41 to the right to set the rivet, then upon building up of a predetermined oil pressure the valve head 123 is opened to allow oil under pressure 40 to enter the cylinder 40 at the right side of piston 42. This causes a movement of the piston 42 to the left and a movement of the inner 45 anvil 160. As the inner anvil moves, its tubular extension 163 forces the ring 153 along the tapered surface 152 in the head on the tubular member, thereby locking the head to the pin in the manner shown in Figs. 15. Increased tension 50 on the pin caused by increased oil pressure subsequently breaks the pin as shown by Fig. 15.

While it has been stated that a drop in oil pressure in cylinder 39 is desirable after the head 21 is formed on the rivet and the plates are tightened, to relax tension on the pin and permit a probable slight movement of the pin in the reverse direction by the inherent resiliency of such head, it may be entirely satisfactory to not have this drop in oil pressure in cylinder 39. The size of oil passages or the operation of the oil pressure supply means, or the character of the valve or such factors conjointly, may be such as to avoid any appreciable drop in oil pressure in cylinder 39 at such stage of the riveting operation. It has been found that rivets may be satisfactorily set without such oil pressure drop in cylinder 39, or in other words, while maintaining the tension on the pin after the head 21 is formed and the plates are drawn together. It seems however that a drop in oil pressure is desirable for reasons previously mentioned.

The machine illustrated is highly efficient for setting rivets of either type and may be used to set rivets very rapidly. It is apparent that movement of the trigger controls all operations after

the rivet is inserted between the jaws, thereby simplifying manual operation of the machine. The flexible oil and air conduits facilitate movement of the rivet setting apparatus relative to the oil pressure supply means, and the apparatus is of such shape and weight as to facilitate its manual manipulation. 5

Although only one form of the invention has been illustrated and described in detail, it will be apparent to those skilled in the art that various 10 modifications may be made without departing from the scope of the appended claims.

We claim:

1. A mechanism for setting a rivet comprising two members, which comprises means for pulling 15 one member, means for applying the reactionary force to the other member, and means for shifting the point of application of the reactionary force.

2. A mechanism for setting a rivet comprising two members, which comprises means for pulling 20 one member, means for applying the reactionary force to the other member, and means for shifting the point of application of the reactionary force while maintaining a pull on the first member.

3. A mechanism for setting a rivet comprising 25 two members, which comprises means for pulling one member, means for applying the reactionary force against the other member, and means for shifting the point of application of the reactionary force on the second member upon a reduction in 30 pulling force on the first member.

4. A machine for setting a rivet of a type comprising a tubular member, and a pin passing through the member and engaging one end thereof, which comprises means for pulling the pin to 35 cause upsetting of the tubular member intermediate its ends, means for applying the reactionary force to the pull against the tubular member, and means for locking the pin and member after said upsetting operation, at a point removed from said 40 point of engagement, while the pin is under tension.

5. A machine for setting a rivet of a type comprising a tubular member, and a pin passing through the member and engaging one end thereof, which comprises means for pulling the pin to 45 cause upsetting of the tubular member intermediate its ends, means for applying the reactionary force to the pull against the tubular member, and means for locking the pin and member after said 50 upsetting operation, at a point removed from said point of engagement, while the tension on the pin is being increased.

6. A machine for setting a rivet wherein the rivet comprises a tubular member adapted to project through openings in and beyond a structure to be riveted, and a pin member engaging the projecting end of the tubular member and passing through the latter and beyond its other end, comprising means for gripping and pulling the projecting end of the pin, means for applying the reactionary force of the pull, against the end of the tubular member adjacent the projecting end of the pin member and means for radially upsetting one member into a recess in the other member, adjacent the projecting end of the pin member, after the pin has been moved through the tubular member sufficiently to form a head out of the latter member at the opposite side of the structure. 65

7. A machine for setting a rivet wherein the rivet comprises a tubular member adapted to project through openings in and beyond a structure to be riveted, and a pin member engaging the projecting end of the tubular member and passing through the latter and beyond its other end, com- 70

prising means for gripping and pulling the projecting end of the pin, means for applying the reactionary force of the pull, against the end of the tubular member adjacent the projecting end of the pin, and means for radially upsetting a part of the tubular member into a recess in the pin member, adjacent the end of the tubular member last mentioned, after the pin has been moved through the tubular member sufficiently to form 10 a head out of such member at the opposite side of the structure.

8. A machine for setting a rivet wherein the rivet comprises a tubular member adapted to project through openings in and beyond a structure 15 to be riveted, and a pin member engaging the projecting end of the tubular member and passing through the latter and beyond its other end, comprising means for gripping and pulling the projecting end of the pin member to form a head out 20 of the body of the tubular member at the opposite side of the structure and then to break the pin intermediate its ends, means for applying the reactionary force of the pull to the end of the tubular member at that side of the structure opposite 25 the head thus formed, and means for locking the members adjacent the last mentioned end of the tubular member, between the head forming and pin breaking operations.

9. A machine for setting a rivet comprising a 30 tubular member adapted to project through and beyond one side of a structure, and a pin engaging one end of the tubular member and projecting through the latter and beyond its other end, which comprises means for gripping and 35 pulling the projecting end of the pin, means for applying the reactionary force to the adjacent end of the tubular member, and means effective after a predetermined pull on the pin sufficient to form a head from the projecting end of the 40 tubular member, to lock the members substantially against relative movement upon release of the pull.

10. A machine for setting a rivet comprising a tubular member adapted to project through and 45 beyond one side of a structure, and a pin engaging one end of the tubular member and projecting through the latter and beyond its other end, and having a breaking point intermediate its ends, which comprises means for gripping and pulling 50 the projecting end of the pin, means for applying the reactionary force to the adjacent end of the tubular member, and means effective after a predetermined pull on the pin sufficient to form a head from the projecting end of the tubular 55 member, and prior to a pull sufficient to break the pin, to lock the members substantially against relative movement upon breaking of the pin.

11. A machine for setting a rivet wherein the latter comprises a tubular member having a pin 60 engaging one end thereof, passing through it and projecting beyond its other end, which comprises means for gripping and pulling the projecting pin portion, means for applying the reactionary force to the adjacent end of the tubular member, and 65 means effective after a predetermined pull on the pin, to modify application of the reactionary force to lock the tubular member to the pin.

12. A machine for setting a rivet wherein the latter comprises a tubular member having a pin 70 engaging one end thereof, passing through it and projecting beyond its other end, which comprises means for gripping and pulling the projecting pin portion, means for applying the reactionary force to the adjacent end of the tubular member, and 75 means effective after a predetermined pull on

the pin, to change the point of application of the reactionary force on the tubular member.

13. A machine for setting a rivet comprising a tubular member adapted to project through a structure and beyond one side of it, and a pin 5 engaging one end of the tubular member, and passing through it and beyond its other end, which comprises fluid pressure operated means for gripping and pulling the projecting pin, means for applying the reactionary force to the adjacent 10 end of the tubular member, and means effective after a predetermined fluid pressure is employed in pulling the pin, for changing the localization of the reactionary force on the tubular member.

14. A machine for setting a rivet comprising a tubular member adapted to project through a structure and beyond one side of it, and a pin engaging one end of the tubular member, and passing through it and beyond its other end, which comprises means for gripping and pulling 20 the pin, means for applying the reactionary force to the adjacent end of the tubular member, secondary means for applying a similar force to the end of the tubular member at a different point, and means for rendering the last means effective 25 after a predetermined pull on the pin.

15. A rivet setting machine for setting a rivet of a type comprising a tubular member and a pin extending therethrough, which comprises means 30 for gripping and pulling the pin, and separate means for applying the reactionary force to the tubular member at different points.

16. A rivet setting machine for setting a rivet of a type comprising a tubular member and a pin extending therethrough, which comprises means 35 for gripping and pulling the pin, and separate anvils for engaging and applying the reactionary force to the end of the tubular member, one of the anvils being adapted to engage the end face of the tubular member and the other anvil being 40 adapted to engage the peripheral surface of the tubular member.

17. A rivet setting machine for setting a rivet of a type comprising a tubular member and a pin extending therethrough, which comprises means 45 for gripping and pulling the pin, separate means for applying the reactionary force to the tubular member at different points, and means for effecting operation of said last mentioned means in sequential order.

18. A rivet setting machine for setting a rivet of a type comprising a tubular member and a pin extending therethrough, which comprises means 55 for gripping and pulling the pin, separate anvils for applying the reactionary force to the end of the tubular member, one of the anvils being adapted to engage the end face of the tubular member and the other anvil being adapted to engage the peripheral surface of the tubular member, and means for effecting operation of said 60 anvils in sequential order.

19. A rivet setting machine for setting a rivet of a type comprising a tubular member and a pin extending therethrough, which comprises means 65 for gripping and pulling the pin, separate anvils for applying the reactionary force to the end of the tubular member, one of the anvils being adapted to engage the end face of the tubular member and the other being adapted to engage the peripheral surface of the tubular member, 70 and means for effecting operation of said anvils in a sequential order depending upon tension applied to the pin.

20. A rivet setting machine for setting a rivet of a type comprising a tubular member having 75

- a head at one end and a pin projecting therethrough for engaging the other end of the tubular member, which comprises means for pulling that end of the pin adjacent said head on the 5 tubular member, means for applying the reactionary force of the pull axially against the head, and means for effecting radial contraction of the head after a predetermined movement of the pin.
21. A rivet setting machine for setting a rivet 10 of a type including a tubular member and a pin extending therethrough, which comprises means for gripping and pulling the pin, means for applying the reactionary force axially against the end of the tubular member, separate means for 15 applying the reactionary force to a different portion of the tubular member after a predetermined movement of the pin, and means enabling a reversed time operation of the two last mentioned means.
22. A rivet setting machine for setting a rivet 20 of a type including a tubular member and a pin extending therethrough, which comprises fluid actuated means for gripping and pulling the pin, means for applying the reactionary force of such pull to the end of the tubular member at one point, and fluid actuated means for changing the localization of application of said reactionary force after a predetermined movement of the pin.
23. A machine for setting rivets of a type including 30 a tubular member and a pin extending therethrough, which comprises fluid actuated means for gripping and pulling the pin, means for applying the reactionary force of such pull to the end of the tubular member at one point, and fluid actuated means for upsetting the metal in a portion of the tubular member after a predetermined movement of the pin.
24. A machine for setting rivets of a type including 35 a tubular member and a pin extending therethrough, which comprises fluid actuated means for gripping and pulling the pin, means for applying the reactionary force of such pull to the end of the tubular member, and fluid actuated means for radially contracting a portion of the tubular member after a predetermined movement of the pin.
25. A machine for setting a rivet of a type including 40 a tubular member and a pin extending therethrough, which comprises fluid actuated means for gripping and pulling the pin, means for applying the reactionary force of such pull to the end portion of the tubular member, fluid actuated means for applying force to another portion of the tubular member, and means rendering the last mentioned fluid actuated means operative upon obtaining a predetermined fluid pressure during actuation of the first fluid actuated means.
26. A rivet setting machine for setting a rivet 45 of a type including a tubular member having a pin extending therethrough, comprising fluid actuated means for gripping and pulling the pin, means for applying the reactionary force of the pull to an end portion of the tubular member, fluid actuated means for applying force to another portion of the tubular member after obtaining a predetermined fluid pressure in connection with the actuation of the first fluid actuated means, and a valve for effecting actuation of the second fluid actuated means upon obtaining said predetermined fluid pressure in connection with the first fluid actuated means.
27. A rivet setting machine for setting a rivet 50 of a type including a tubular member having a pin extending therethrough, comprising fluid actuated means for gripping and pulling the pin, means for applying the reactionary force of the pull to an end portion of the tubular member, fluid actuated means for applying force to another portion of the tubular member after obtaining a predetermined fluid pressure in connection with the actuation of the first fluid actuated means, and a valve for effecting actuation of the second fluid actuated means upon obtaining said predetermined fluid pressure in connection with the first fluid actuated means.
28. A machine for setting a rivet of a type comprising 55 a tubular member and a pin extending therethrough and wherein the pin is adapted to be broken after setting of the rivet, which comprises a casing, separate fluid actuated means movable in the casing, one of which is adapted to grip and pull the pin and finally break it, and the other of which is adapted to apply reactionary force to the pull against the tubular member, and means for controlling the operation of said fluid actuated means.
29. A machine for setting a rivet of a type comprising 60 a tubular member and a pin extending therethrough, fluid actuated means for gripping and pulling the pin and including a piston and a piston rod, and a second fluid actuated means for applying reactionary force of the pull to a portion of the tubular member, said second fluid actuated means including a piston slidably mounted on said piston rod.
30. A machine for setting a rivet of a type including 65 a tubular member and a pin extending therethrough wherein the pin is adapted to be broken after setting of the rivet, which comprises fluid actuated means for gripping and pulling the pin, means for applying the reactionary force to an end portion of the tubular member, fluid actuated means for changing the localization of application of said reactionary force after obtaining a predetermined movement of the pin and before breaking thereof, and means for rendering said fluid actuated means ineffective following breaking of the pin and after a predetermined movement thereof.
31. A machine for setting a rivet of a type including 70 a tubular member and a pin extending therethrough, fluid pressure actuated means for gripping and pulling the pin, means for applying the reactionary force to an end portion of the tubular member, fluid actuated means for applying an upsetting force to another portion of the tubular member, a source of supply of fluid under pressure, and fluid pressure control means for automatically effecting operation of the fluid actuated means in sequence.
32. A machine for setting rivets or the like 75 wherein an element is pulled and the reactionary force is applied against another element, which comprises a casing, a pair of fluid pressure responsive means movably carried by said casing for pulling the element and applying the reactionary force respectively, and means for introducing fluid pressure to the fluid pressure responsive means.
33. A machine for setting rivets or the like 80 wherein an element is pulled and the reactionary force is applied against another element, which comprises a casing, a pair of fluid pressure responsive means movably carried by said casing for pulling the element and applying the reactionary force respectively, and means for introducing fluid pressure to the fluid pressure responsive means.

and equalizing the pressure on both responsive means so that one is balanced against the other.

34. A machine for setting rivets wherein one element is pulled and the reactionary force is applied against another element, which comprises power operated means for pulling the first element, means for applying the reactionary force to the other element, manual control means for governing operation of the power means, and means governed by movement of the power means for interrupting operation of the control means.

35. A machine for setting rivets wherein one element is pulled and the reactionary force is applied to another element, comprising means for pulling the first element, dual means for applying the reactionary force to the other element, and means rendering said dual means selectively operable.

36. A machine for setting rivets wherein one element is pulled and the reactionary force is applied to another element, comprising means for pulling the first element, dual means for applying the reactionary force to the other element, and means rendering said dual means selectively operable without changing their relative positions.

37. A machine for setting rivets wherein one element is pulled and the reactionary force is applied to another element, comprising means for pulling the first element, a pair of anvils one within the other for applying the reactionary force to the other element, and means rendering said anvils selectively operable.

38. A machine for setting rivets wherein one element is pulled and the reactionary force is applied to another element, comprising means for pulling the first element, a pair of anvils one within the other for applying the reactionary force to the other element, and means rendering said anvils selectively operable without changing their relative positions.

39. A machine for setting rivets wherein one element is pulled and the reactionary force is applied to another element, comprising means for pulling the first element, inner and outer sleeves having anvils for applying the reactionary force to the other element, and means for rendering said anvils selectively operable by turning the sleeves.

40. A machine for setting rivets wherein one element is pulled and the reactionary force is applied to another element, comprising means for pulling the first element, inner and outer sleeves having anvils for applying the reactionary force to the other element, means retaining said sleeves against relative turning movement but permitting relative sliding movement thereof, and means rendering said anvils selectively operable by turning the sleeves as a unit.

41. A machine for setting rivets wherein one element is pulled and the reactionary force is applied to another element, comprising fluid actuated means for pulling the first element, dual means for applying the reactionary force to the other element, fluid actuated means for operating the dual means, and means rendering the fluid actuated means operable for actuating the dual means selectively.

42. A machine for setting rivets or the like wherein one element is pulled and the reactionary force is applied to another element, comprising a casing having dual compartments, fluid pressure responsive means in each compartment, a source of fluid under pressure, means for introducing fluid under pressure into one compartment, con-

trol means for introducing fluid under pressure into the other compartment when the fluid pressure in the first compartment reaches a predetermined amount, and means for allowing fluid to flow from the second compartment into the first when the pressure in the former is greater than in the latter.

43. A machine for setting rivets or the like wherein one element is pulled and the reactionary force is applied to another element, comprising a casing having dual compartments, fluid pressure responsive means in each compartment, a source of fluid under pressure, means for introducing fluid under pressure into one compartment, control means for introducing fluid under pressure into the other compartment when the fluid pressure in the first compartment reaches a predetermined amount, and means for allowing fluid to flow from the second compartment into the first when the pressure in the former is greater than in the latter, said last mentioned means being operable independently of the control means.

44. A machine for setting rivets or the like which comprises a casing, fluid pressure responsive means in the casing, a liquid fluid pressure line connected to the casing at one side of the fluid pressure responsive means, a gaseous fluid pressure line connected to the casing at the other side of the fluid pressure responsive means, means operable by reduction of the pressure in the gaseous fluid line for introducing liquid fluid into the casing at a pressure sufficient to move the pressure responsive means against the gaseous pressure at the other side of the responsive means, and means for substantially preventing exhaust of the gaseous fluid at said other side of the responsive means even though the pressure in the gaseous fluid line is reduced.

45. A machine for setting rivets wherein one element is pulled and the reactionary force is applied to another element, comprising a casing having different compartments, fluid pressure responsive means in each compartment, a fluid pressure source adapted to be connected to the compartments, means connected to one fluid pressure responsive means for pulling the first element, a pair of anvils for applying the reactionary force to the other element, means operatively connecting one anvil to the casing so as to initially apply the reactionary force through the casing and said anvil, means operatively connecting the other anvil to the other fluid pressure responsive means, and means operative upon supplying a predetermined fluid pressure to the first responsive means for introducing fluid under pressure to the second responsive means so as to cause the second anvil to become operative for applying the reactionary force.

46. A rivet setting machine comprising a casing, means in the casing for pulling a rivet element or the like, a pair of anvils for applying the reactionary force of the pull against another element, and means operatively connecting the anvils selectively to the casing so that either anvil may apply the reactionary force.

47. A rivet setting machine comprising a casing, means in the casing for pulling a rivet element or the like, a pair of anvils for applying the reactionary force of the pull against another element, and means operatively connecting the anvils selectively to the casing so that either anvil may apply the reactionary force, said means comprising inner and outer sleeves having projections, and projections on the casing adapted

selectively to engage the projection on one sleeve or the projection on the other sleeve.

48. A rivet setting machine comprising a casing, means in the casing for pulling a rivet element or the like, a pair of anvils for applying the reactionary force of the pull against another element, and means operatively connecting the anvils selectively to the casing so that either anvil may apply the reactionary force, said means comprising inner and outer sleeves slidable one on the other, a radial projection on one sleeve slidably arranged in an axial slot in the other sleeve, and means on the casing adapted to selectively engage said projection on the one sleeve or the end of the other sleeve.

49. A machine for setting a rivet wherein one element is pulled and the reactionary force is applied to another comprising a casing, means in the casing for pulling the first element, inner and outer sleeve members slidably mounted one on the other for applying the reactionary force, one or more axial projections on one sleeve, one or more axial projections on the other sleeve slidably between said projections on the first sleeve, one or more projections on the casing for selectively engaging said projections on the first sleeve or the projections on the second sleeve, and releasable means for holding the sleeves against turning but permitting turning adjustment thereof so that the projections on the casing may optionally be engaged either with the projections on the second sleeve or projections on the first sleeve.

50. A machine for setting a rivet wherein one element is pulled and the reactionary force is applied to another comprising a casing, means in the casing for pulling the first element, inner and outer sleeve members slidably mounted one on the other for applying the reactionary force, one or more axial projections on one sleeve, one or more axial projections on the other sleeve slidably between said projections on the first sleeve, one or more projections on the casing for selectively engaging said projections on the first sleeve or the projections on the second sleeve and means in the casing adapted to cooperate with the projections on the sleeve not engageable with the projections on the casing, for applying the reactionary force through said sleeve.

51. A machine for setting a rivet wherein one element is pulled and the reactionary force is applied to another comprising a casing, means in the casing for pulling the first element, inner and outer sleeve members slidably mounted one on the other for applying the reactionary force, one or more axial projections on one sleeve, one or more axial projections on the other sleeve slidably between said projections on the first sleeve, one or more projections on the casing for selectively engaging said projections on the first sleeve or the projections on the second sleeve and means for effecting application of the reactionary force first through the casing to the sleeve in engagement with the projections on the casing, and then through the other sleeve.

52. A machine for setting a rivet wherein one element is pulled and the reactionary force is applied to another comprising a casing, means in the casing for pulling the first element, inner and outer sleeve members slidably mounted one on the other for applying the reactionary force, one or more axial projections on one sleeve, one or more axial projections on the other sleeve slidably between said projections on the first sleeve, one or more projections on the casing for

selectively engaging said projections on the first sleeve or the projections on the second sleeve, and means for effecting application of the reactionary force first through the casing to the sleeve in engagement with the projections on the casing, and then through the other sleeve, said last mentioned means being operable after a predetermined pull on the element is effected.

53. A machine for setting rivets or the like wherein one element is pulled and the reactionary force is applied to the other element comprising a casing, fluid pressure responsive means in the casing for pulling the first element, and a separate fluid pressure responsive means movable relative to the casing for applying the reactionary force to the other element.

54. A fluid pressure operated rivet setting mechanism comprising a casing having aligned but separated cylinders, pistons in the cylinders, a rod slidable in both cylinders and being slidable through one piston and connected to the other, and separate rivet engaging elements operatively connected respectively to said rod and said one piston.

55. A riveting machine comprising a jaw holder having convergently related sockets for slidably receiving a plurality of circumferentially arranged jaws, jaws slidably engaging in the sockets, means for urging the jaws toward the converging ends of the sockets, and means at the outermost ends of the jaws for locking them substantially against relative axial movement.

56. A riveting machine comprising a jaw holder having convergently related sockets for slidably receiving a plurality of circumferentially arranged jaws, jaws slidably engaging in the sockets, means for urging the jaws toward the converging ends of the sockets, and means at the outermost ends of the jaws for locking them substantially against relative axial movement, said last mentioned means comprising recesses in the inner surfaces of the jaws and holding means disposed in the recesses.

57. A riveting machine comprising a jaw holder having convergently related sockets for slidably receiving a plurality of circumferentially arranged jaws, jaws slidably engaging in the sockets, means for urging the jaws toward the converging ends of the sockets, and means at the diverging ends of the jaws for locking them substantially against relative axial movement, said last mentioned means comprising a tubular element projecting between the diverging ends of the jaws, and radially interengaging projections on the jaws and tubular member.

58. A machine for setting rivets or the like, comprising an outer jaw contracting member having inner converging jaw surfaces, a reciprocating member connected to said member for moving it, separate jaws between said surfaces having outer surfaces engaging the surfaces on the member, and means slidably mounted on the reciprocating member and having axially interlocking engagement with the jaws while permitting the jaws to contract or expand radially.

59. A machine for setting rivets or the like, comprising an outer jaw contracting member having inner converging jaw surfaces, a reciprocating member connected to said member for moving it, separate jaws between said surfaces having outer surfaces engaging the surfaces on the member, and means slidably mounted on the reciprocating member and having axially interlocking engagement with the jaws while permitting the jaws to

contract or expand radially, said means comprising a tubular element.

60. A machine for relatively moving a pair of members, one projecting from the other, comprising means for gripping and pulling the projecting member, means for applying the reactionary force to the other member, and means effective after predetermined movement of the projecting member for causing the second means to apply radially contractile forces to the other member.

61. A machine for relatively moving a pair of members, one projecting from the other, comprising means for gripping and pulling the projecting member, means for applying the reactionary force to the other member, and means effective after predetermined tension on the projecting member for causing the second means to apply radially contractile forces to the other member.

62. A machine for setting a rivet or the like wherein the rivet comprises a tubular member having a head on one end and a pin passing through the tubular member and adapted to engage the opposite end of the tubular member and to project from said head, which comprises means for gripping and pulling the projecting end of the pin, means for applying the reactionary force to the head on the tubular member, and means for causing the last mentioned means to effect movement of metal in the head radially towards the pin after a predetermined axial movement of the pin has occurred.

63. A machine for setting a rivet or the like wherein the rivet comprises a tubular member having a head on one end and a pin passing through the tubular member and adapted to engage the opposite end of the tubular member and to project from said head, which comprises means for gripping and pulling the projecting end of the pin, means for applying the reactionary force to the head on the tubular member, and means for causing the last mentioned means to effect movement of metal in the head radially towards the pin after a predetermined tension on the pin has been obtained.

64. A machine for setting a rivet or the like wherein the rivet comprises a tubular member having a head on one end and a pin passing through the tubular member and adapted to engage the opposite end of the tubular member and to project from said head, which comprises means for gripping and pulling the projecting end of the pin, means for applying the reactionary force to the head on the tubular member including an anvil having a tapered wall socket adapted to move over the head and contract portions of the head toward the pin, and means for effecting such movement of anvil after a predetermined movement of the pin.

65. A machine for setting a rivet or the like wherein the rivet comprises a tubular member having a head on one end and a pin passing through the tubular member and adapted to engage the opposite end of the tubular member and to project from said head, which comprises means for gripping and pulling the projecting end of the pin, means for applying the reactionary force to the head on the tubular member including an anvil having a tapered wall socket adapted to move over the head and contract portions of the head toward the pin, and means for effecting such movement of anvil after a predetermined tension on the pin has occurred.

66. In combination, a valve chamber having an intake port and an exhaust port, an integral valve member adapted to maintain both of said

ports closed at the same time, spring means for urging said member into port closing position, said member being adapted to open said exhaust port in response to a predetermined pressure within said valve chamber, and to open said intake port in response to an external pressure which exceeds by predetermined amount that required to effect opening of the exhaust port.

67. A machine for setting rivets of the type wherein one rivet element is pulled and the reaction force is applied to the other element, including means for gripping and pulling said one element, means for applying the reaction force to and swaging the other element to the first element, and means for ejecting the rivet elements from the second named means upon completion of the swaging operation.

68. A machine for setting rivets wherein one rivet element is pulled and the reaction force is applied to the other element to effect the setting operation including, means to grip the first element, a swaging anvil adapted to engage the other element and swage the rivet elements together, thrust means adapted to engage the other element independently of said swaging anvil, means to exert a pulling force on said gripping means and a reaction force on said swaging anvil to effect the swaging operation, and means operable when said swaging operation is completed for exerting pulling force on said anvil and a reaction force on said thrust means to withdraw said swaging anvil from said other element.

69. A machine for setting a rivet wherein a rivet element is pulled, and the reactionary force is applied to another element, including means to grip the first element, a thrust member adapted to engage and transmit the reaction force to the other element, an anvil adapted to engage the other element independently of said thrust member and transmit the reaction force to the other element for the purpose of deforming the same, fluid pressure means for applying a pulling and reaction force to said gripping means and thrust member respectively to move said members relatively and perform one of the rivet setting operations, means operable automatically upon completion of said movement to shift the reactive force from the thrust member to the anvil whereby said anvil, under the influence of said reactive force, will perform a second rivet setting operation, and fluid pressure means operable upon completion of the rivet setting operation for exerting a pulling force on said anvil and a reactive force on said thrust member whereby said thrust member will eject the other rivet member from said anvil.

70. A machine for setting rivets wherein a rivet is set by applying a pulling force to one element thereof and a reaction force to another element thereof, comprising a cylinder, a piston and piston rod in said cylinder, means to grip the first rivet element operatively connected to said rod, a sleeve on said rod carrying a second piston in said cylinder, an anvil operatively connected to said sleeve and adapted to engage the other rivet element and swage the elements together, a thrust member fixedly connected to the cylinder and adapted to engage the other rivet element independently of said anvil, means to apply fluid pressure between said pistons to effect the swaging operation, and means to provide a pressure between said second piston and the adjacent cylinder wall in excess of that between the pistons for ejecting the other element from the anvil.

71. A machine for setting rivets wherein one

- element is pulled and the reactionary force is applied to another element, comprising dual means for applying the reactionary force to the other element, means for successively operating 5 said dual means, and means permitting change of the order of succession of operation of said dual means by said last named means.
72. A machine for setting rivets wherein one element is pulled and the reactionary force is applied to another element, comprising means for pulling the first element, a pair of anvils, one within the other, for applying reactionary force to the other element, means for successively operating said anvils, and means permitting change 10 of the order of succession of operation of said anvils by said last named means.
73. In combination, a cylindrical valve chamber having an intake port at one end and a lateral exhaust port, a cylindrical valve fitting in said cylinder and adapted to control said exhaust port, a projection of reduced diameter on said valve extending in the direction of the axis thereof and adapted to control said intake port, said valve and projection being so arranged that both ports 15 may be maintained closed at the same time, and resilient means urging said valve into port closing position.
74. A mechanism for setting a rivet comprising two members which include means for pulling one member, means for applying the reactionary force against the other member, and means for shifting the point of application of the reactionary force on the second member upon an increase in the pulling force on the first member.
75. A machine for setting a rivet of a type comprising a tubular member and a pin passing through the member and having an axial abutment against one portion thereof, including 20 means for pulling the pin to deform one portion of the tubular member, and means for applying a reactionary force to said tubular member, said last named means being effective to lock the tubular member and pin together upon completion of the deformation of the tubular member.
76. A machine for setting a rivet of a type comprising a tubular member and a pin passing through the member and engaging one end 25 thereof, including means for pulling the pin to cause the pin to collapse and bulge outwardly the tubular member to form a head thereon, and means for applying the reactionary force to said tubular member, said last named means being 5 effective to move the metal of the tubular member radially inwardly toward the pin when the aforesaid head is formed on the tubular member.
77. A machine for setting a rivet of the type comprising inner and outer cooperating members, including, means for gripping and exerting a pulling action on the inner rivet member, and means for transmitting the reactive force to the outer member adapted to cause an inward flow 10 of the material of the outer member into engagement with the inner member.
78. A machine for setting rivets of the type comprising a tubular member and a pin extending therethrough, which comprises mechanism for gripping and pulling the pin, a pair of anvils 20 for applying a reactionary force to the tubular member, one of said anvils being adapted to swage the tubular member on to the pin, and means for effecting operation of said anvils in sequential order during pulling of the pin with 25 said one anvil being operated after the other.
79. A machine for setting rivets wherein one element is pulled and a reactionary force is applied to another element, comprising a casing, a pair of fluid pressure responsive means carried by said casing, means connected to one fluid pressure means for pulling the first element, a pair of anvils for applying reactionary forces to the other element, means operatively connecting one anvil to the casing so as to initially apply a 30 reactionary force through the casing and said anvil, means operatively connecting the other anvil to the other fluid pressure responsive means, and means operative upon supplying a predetermined pressure to the first responsive means for introducing fluid under pressure to the second responsive means so as to cause the second anvil to become operative for applying a reactionary force.
